UNITED STATES PATENT OFFICE.

RICHARD G. HARRIS, OF BEARDEN, TENNESSEE, ASSIGNOR OF ONE-THIRD TO JAMES W. HILL AND ONE-THIRD TO IRA W. HILL, BOTH OF BEARDEN, TENNESSEE.

MINER'S LAMP.

1,109,415.

Specification of Letters Patent. Patented Sept. 1, 1914.

Application filed December 13, 1913. Serial No. 806,614.

To all whom it may concern:

Be it known that I, RICHARD G. HARRIS, a citizen of the United States, residing at Bearden, in the county of Knox and State 5 of Tennessee, have invented new and useful Improvements in Miners' Lamps, of which the following is a specification.

This invention relates to improvements in miners' lamps and has particular application to a combination lamp and cap.

In carrying out the present invention, it is my purpose to provide a combination miner's lamp and cap wherein the lamp and cap will be connected to each other in such 15 manner as to present a unitary structure and wherein the connection between the cap and the lamp will be fixed so that accidental disconnection of the parts is eliminated.

It is also my purpose to provide a device 20 of the class described which will embody an electric lamp and a cap so constructed and arranged that the device may be readily and conveniently handled and worn, while derangement of the parts incident to jarring 25 and the like is avoided.

With the above and other objects in view, the invention consists in the construction, combination and arrangement of parts hereinafter set forth in and falling within the 30 scope of the claims.

In the accompanying drawing, Figure 1 is a perspective view of a device constructed in accordance with the present invention. Fig. 2 is a similar view, the flexible covering 35 of the cap being removed. Fig. 3 is a longitudinal sectional view through the lamp and connections between the lamp and the frame of the cap, the parts being shown enlarged. Fig. 4 is a transverse sectional view 40 through the lamp structure.

Referring now to the drawing in detail, 1 designates a cap plate of cylindrical outline and having a series of apertures 2 formed therein adjacent to the periphery 45 thereof, while 3 indicates a series of ribs each having one end fastened in one of the apertures 2 in the cap plate and the opposite end secured to an annular ring or band 4. The band 4, ribs 3 and the cap plate 1

50 constitute a metallic framework for the cap structure and such framework conforms to the contour of the head and is incased in a cloth covering 5. The band 4 is preferably provided with an outwardly extending peak

like frame 6 covered with suitable cloth and forming the peak of the cap.

At diametrically opposite points, the cap plate 1 is formed with connecting ears 7, 7 and soldered or otherwise connected to such ears and disposed upon the under surface 60 of the cap plate is a cylindrical tube 8 projecting through the cap structure at the front and rear thereof and having the front end suitably connected with a socket 9 carrying a reflector 10 and a lamp bulb 11 within 65 such reflector. The rear end of the tube 8 is threaded interiorly to receive a plug 12 connected through the medium of a chain 13 with a button 14 on the upper surface of the cap plate, the chain serving to prevent 70 loss of the plug when the latter is removed from the tube.

Slidably mounted within the tube 8 is a container 15 carrying a battery 16 and provided with a laterally projecting pin 18 75 working within a slot 19 formed in the tube 8, the opposite ends of the slot being arranged at right angles to the center portion thereof as at 20. The forward end of the 80 slideable container 15 is provided with contacts 21 connected with the terminals of the battery 16 and designed to engage the terminals of the lamp socket 9 when the battery and container are moved toward the forward end of the tube 8 so as to energize 85 the lamp.

In practice, the parts are assembled as illustrated in Figs. 2 and 3 and when the miner desires to illuminate the lamp the pin 18 is moved from the rear end of the slot 19 toward the front end thereof and disposed within the forward right angular end portion of such slot. In the forward movement of the pin, the container 15 and battery 16 therein move into engagement with the 95 lamp socket thereby connecting the battery in circuit with the lamp so that the latter is illuminated and the rays thereof projected outwardly by means of the reflector 10, the pin resting within the forward right angular portion of the slot 19 serving to prevent the breaking of the circuit. 100

From the foregoing description taken in connection with the accompanying drawing, the construction and manner of employing 105 my invention will be readily apparent. It will be seen that I have provided a combination miner's lamp and cap wherein the

cap and lamp structures form a unit and wherein the parts are rigidly connected together so that mutilation of the structure is eliminated.

5. I claim:

1. A miner's lamp comprising a tube, a socket member connected to one end of said tube, a lamp bulb carried by said socket member, a reflector surrounding said bulb, a 10 container mounted within said tube and capable of sliding movement therein, a battery within said container, and means for sliding said container to connect said battery with said socket whereby the lamp will 15 be illuminated.
2. A miner's lamp comprising a tube, a

socket member connected to one end of said tube, a lamp bulb carried by said socket member, a reflector surrounding said bulb, a container mounted within said tube and 20 capable of sliding movement therein, a battery within said container, means for sliding said container to connect said battery with said socket whereby the lamp will be illuminated, and means for locking said container 25 against movement.

In testimony whereof I affix my signature in presence of two witnesses.

RICHARD G. HARRIS.
